AUTOMATIC PARKING LIGHT SWITCH

Filed April 18, 1927

Fig. 3.

179: 41 Southgate Bay Wharf.

UNITED STATES PATENT OFFICE

JAMES A. SARTELLE, OF LANCASTER, MASSACHUSETTS

AUTOMATIC PARKING-LIGHT SWITCH

Application filed April 18, 1927. Serial No. 184,612.

This invention relates to a device which can be set for any hour and will operate to turn on the parking lights of an automobile or any other desired electrical device 5 at that hour without any further attention.

The principal object of the invention is to provide mechanism for accomplishing the above mentioned purpose, so that a person leaving an automobile in the day-time, 10 knowing that he will have to stay away until after dark, can have his parking lights start to burn at any time he desires and will not have to leave the lights on in the day-time, thus running down his battery. The invention 15 is capable of other analogous uses. The invention also involves combinations of parts and features of construction as will appear hereinafter.

Reference is to be had to the accompanying drawings in which

Fig. 1 is a central sectional view of the operating mechanism in its preferred form and showing in elevation other elements which are to be used in connection with this 25 invention;

Fig. 2 is an edge elevation of the contact element of the device;

Fig. 3 is a front view showing the parts in neutral position; and

Fig. 4 is a similar view showing the parts set to have the lights go on at a certain time.

It is an inconvenience for many people, who have to park their automobiles for several hours, to have to go back and turn on 35 the parking lights at dark. This is a matter of so much inconvenience that many of them leave the lights burning for several hours in day-light in order that they will be sure that they will be on when it grows 40 dark. This involves the running down of the battery and the loss of energy in that way. By the present invention these difficulties are avoided.

This invention involves the use of a clock 45 10 of any ordinary kind mounted on the dash and with it a dial 11 on the dash just above it preferably. The face of the clock 12 is shown just below the dial 11. The dial is provided with a pointer 13 mounted on a 50 knurled head 14 and both are secured on a

shaft 15. The shaft 15 is connected by gears 16 all of the same size to a hollow hub 17 of a contact member 18. The shafts are insulated from the supporting casing 36. This contact member is shown as of cylindrical cup-shape and is made of vulcanized fiber or any other strong and durable insulating material. On the outside it is provided with a conducting ring 19 extending all the way around it and on the inside with a conducting strip 20 extending preferably two-thirds of the way around it. These two curved strips are riveted together through the flange of the member 18, thus connecting them electrically. 55

It is to be understood that this contact member 18 is adapted to be turned by the knob 14 with the pointer 13 as will appear from a comparison of Figs. 3 and 4. In Fig. 3 the parts are set at zero or neutral, and the conducting strip 20 is shown with its end at the twelfth hour on the clock face 12. When the pointer 13 is turned around to 8 on the dial, the strip 20 is turned around to the position shown in Fig. 4. This can be done irrespective of the time if the operator wishes his lights to go on at eight o'clock. The time at which the instrument is set is indicated in these two figures as five minutes past five, but the setting will be no different no matter what the time. The object is to have the clock run and turn a contact spring 27 with the hour hand and at eight o'clock bring the contact spring 27 around into contact with the conducting strip 20 to make a circuit so that the lights will go on at that time. 70

For this purpose, the shaft 21 of the clock is shown as having a gear 22 meshing with a gear 29 for driving a shaft 23 which is concentric with the contact member 18 and the hub thereof. This shaft 23 through a large gear shown on that shaft is provided with a cup-shaped contact 24 which rotates with it preferably, and is also provided with a flat insulating disc 25 which has a conducting arm 26 from the hub 24 to the edge of the disc where it is provided with the contact spring 27 which is spring-pressed and will engage the contact strip 20. This disc, it 75 80 85 90 95 100

will be seen, rotates with the clock and at the same speed as the hour hand, the gearing being so designed.

Projecting into the cup-shaped contact 24 5 is a light spring contact member 30 on a stud 31 on which the hub of the contact member 18 is mounted and from which it is insulated by a bushing 32. The end of this stud 31 is connected with one end of the line 10 33 which is connected up with the parking lights and the battery so as to turn them on whenever circuit is completed. The other line 34 is connected with a block 35 insulated from the casing 36 in which these parts are 15 mounted, and having a contact brush 37 which constantly engages the external ring 19.

It will be seen that when the spring 27 is 20 in engagement with the strip 20 there will be a current from the line 33, stud 31, contacts 30 and 24, arm 26, spring 27 to the strip 20. The ring 19 is always in contact with the brush 37 and line 34 and is connected with the strip 20 by the rivets.

It will be understood also that after the 25 contact member 18 is once set as indicated in Fig. 4, this remains stationary and the disc 25 rotates slowly with the hour hand of the clock. Therefore, during the time when the spring 27 is not in engagement with the strip 30 20 there will be no lighting current as the circuit will be broken at that point, but when the spring 27 comes around into contact with the strip 20 the circuit will be completed and the lights will burn for eight hours unless 35 shut off. In this way the operator can leave his car and, as long as the clock is wound up and going, he will be sure that the parking lights will be turned on at any time he may desire and will continue to burn all night if 40 necessary. A snap switch is used to cut this circuit when it is not to be used, as usual.

This constitutes a simple and inexpensive 45 device for accomplishing these important results. With the strip 20 extending two thirds of the way around the contact member 18, the device can be set to light up the lamps four hours or less after the time at which the user leaves his car. There are only a few parts 50 driven by the clock and the contact making devices pressing on them are light and apply only a light spring pressure so no material burden is thrown on the works of the clock.

This invention can be used as a time switch 55 for other purposes and I do not wish to be limited to the turning on of parking lights, although that is the principal use for which the invention is designed.

Although I have illustrated and described 60 only a single form of the invention I am aware of the fact that changes can be made therein by any person skilled in the art without departing from the scope of the invention as expressed in the claim.

Therefore I do not wish to be limited to the 65 exact form shown, but what I do claim is:—

In a timing switch, the combination of a circular contact member of insulating material having a conducting ring around it and a conducting strip part way around it electrically connected with the ring, means for setting the contact member in any desired position about its axis, a rotary member having a contact spring adapted to rotate along the path of the conducting strip, means having a rubbing engagement with the center of the 70 rotary member for connecting the contact spring with one side of an electric circuit, and a spring contact in engagement with the conducting ring for connecting the conducting ring constantly with the other side of said 75 circuit.

In testimony whereof I have hereunto affixed my signature.

JAMES A. SARTELLE.
